US0D1014022S

(12) **United States Design Patent** (10) **Patent No.:** **US D1,014,022 S**
(45) **Date of Patent:** **** Feb. 13, 2024**

(54) **SHOE**

(71) Applicant: **ROTHY'S, INC.**, San Francisco, CA (US)

(72) Inventor: **William Roth Martin**, San Francisco, CA (US)

(73) Assignee: **ROTHY'S, INC.**, San Francisco, CA (US)

(**) Term: **15 Years**

(21) Appl. No.: **29/825,363**

(22) Filed: **Jan. 31, 2022**

Related U.S. Application Data

(62) Division of application No. 29/721,508, filed on Jan. 21, 2020, now Pat. No. Des. 946,250.

CLAIM

The ornamental design for a shoe, as shown and described.

DESCRIPTION

FIG. 1 is front left perspective view of a shoe showing my new design;

FIG. 2 is front view of the design shown in FIG. 1;

FIG. 3 is a rear view of the design shown in FIG. 1;

FIG. 4 is a right side view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

The broken lines shown in the figures are included for the purpose of illustrating portions of the shoe that form no part of the claimed design.

1 Claim, 7 Drawing Sheets
